UNITED STATES PATENT OFFICE.

CHARLES B. RAUCH, OF DAYTON, OHIO.

STRINGED MUSICAL INSTRUMENT.

1,001,302.

Specification of Letters Patent. Patented Aug. 22, 1911.

Application filed January 25, 1911. Serial No. 604,537.

To all whom it may concern:

Be it known that I, CHARLES B. RAUCH, a citizen of the United States, residing at Dayton, in the county of Montgomery and State of Ohio, have invented certain new and useful Improvements in Stringed Musical Instruments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in the construction of musical instruments such as mandolins and guitars. The improvements are applicable to the great range of stringed instruments, such as violins, mando-cellos, cellos, etc.

The main object of the invention is to increase the vibrating power of the instrument so that the musical sound waves shall have a greater volume and range of travel. In carrying out this object I so construct the front sounding board and the back board that there is but a single glued joint uniting them. This preserves to a greater extent the natural grain of the wood from which these parts are constructed. And further, I interpose on the interior of the instrument a diaphragm which is thinner at its circumference than elsewhere and constitutes a delicate sounding board. The sound waves impinge against this sensitive member, and are thus prevented from contacting with the back of the instrument which is deadened by being held against the person of the performer.

In the accompanying drawings I have illustrated a mandolin constructed in accordance with the above briefly described features, and will now describe more in detail the essential features both as to structure and functions.

In said drawings, Figure 1 is a plan view of a mandolin with the neck and a portion of the front sounding board broken away. Fig. 2 is a sectional view on the line *a a* of Fig. 1, looking in either direction. Fig. 3 is an edge elevation of the instrument, showing the single joint between the meeting edges of the front sounding board and the back. Fig. 4 is a transverse sectional view on the line *b b* of Fig. 1.

Referring to the specific parts as illustrated in the drawings and as indicated by reference characters, 1 designates the front board, otherwise termed the front sounding board. This element is preferably constructed of a character of wood which is conspicuous on account of its freedom from an abundance of sap, such wood for example as balsam, fir and the like. This front sounding board is carved from a single piece of such material with the circumference terminated in a laterally turned rim 2. In constructing said board in such manner and extending the rim 2 around the edge of the instrument, the natural grain of the wood is not intercepted at any point as would be the case were the laterally extended rim 2 eliminated and a separate piece of material joined thereto to constitute such rim. The usual sound opening 3 and string supporting bridge 4, are provided in and on said front sounding board. The front portion 1 of said front sounding board is left with more body or material in order that a suitable reinforcement may be provided to support the finger-board neck 5. The back board 6 is carved similarly to the front sounding board, though the selection of wood is not so important in the construction of this member. Like the front sounding board 1, it is carved from a single piece of wood with the margin extended in a rim 6'. The rim 6' and the rim 2 of the front sounding board, are united by means of glue, and thus it will be seen there is a single joint which unites the front and back of the instrument. The front portion 6' of the back is left with a suitable thickness, which combines with the similarly constructed portion 1' of the front sounding board in providing a suitably reinforced portion for the support of the finger-board neck 5. Like the front board 1, the natural course of the grain of the wood from which the back board is constructed, is not interfered with, but these two members are extended until their edges meet.

The reinforcement for the tail piece consists of a block 7 interposed between the ends of the front and back boards 1 and 6, and there secured by means of glue. This reinforcing block 7 might extend in equal parts from the front and back boards and thus be integral parts of said boards. The object and purpose of the said reinforcing block is well understood and requires no

further reference than the statement that pin 8', entering said block, holds one side of the tail piece while the strings of the instrument are connected with the other side. 5 Such features being no part of the present invention and being unnecessary for a proper elucidation of the invention, the strings and tail piece are omitted from the drawings.

Coming now to a very important feature 10 of my improvement, it will be seen from Figs. 1 and 2 that the inner side of the back board 6 is provided with a ledge 8. This ledge extends entirely around near the circumference of said board, and provides a 15 support to which a diaphragm 9 is glued. This diaphragm lies below the joint uniting the front and back boards, and it constitutes an inner sounding board. The circumference of this member is the only part which 20 is in contact with any part of the structure, and owing to this and its construction, it has a most delicate vibratory quality. The peculiar construction of this member consists in forming the lower surface in convex, 25 while the upper side is substantially flat or level. This produces a thin circumferential edge which alone engages the ledge 8. The location of this inner sounding board and its effect is such as to prevent the sound waves 30 from impinging against the back of the instrument which has little or no vibratory quality. This must necessarily be the case when we consider that the backs of such in-

struments are usually constructed with a first view to durability and not so much with a view to obtaining vibratory action and lasting resonance. Suitable openings 10 are provided in the inner sounding board or diaphragm to relieve the dead air chamber which would otherwise exist between said 40 diaphragm and the back of the instrument. The inner sounding board being thus of delicate construction and free from any resisting pressure below it, responds to the sound waves in a manner which gives great carry- 45 ing effect to the tones produced.

Having described my invention, I claim:

A stringed musical instrument having its body formed of two equal parts united by a middle circumferential joint, the back portion of said body being provided with a marginal rabbet which extends continuously around the inner side of said back portion and forms thereon an integral offset lying on one side of said circumferential joint, and a plano-convex sounding board having its relatively thin circumferential portion supported on said offset, substantially as 55 specified.

In testimony whereof I affix my signature, 60 in presence of two witnesses.

CHARLES B. RAUCH.
